US0D1100396S

(12) **United States Design Patent** (10) Patent No.: **US D1,100,396 S**
(45) Date of Patent: ** Oct. 28, 2025

(54) **FACIAL SCRUBBING DEVICE**

(71) Applicant: **Sud Scrub Inc.**, San Gabriel, CA (US)

(72) Inventors: **Raymond Truong**, Las Vegas, NV (US); **Steven Truong**, Las Vegas, NV (US)

(73) Assignee: **Sud Scrub Inc.**, San Gabriel, CA (US)

(**) Term: **15 Years**

(21) Appl. No.: **29/889,451**

(22) Filed: **Apr. 12, 2023**

(51) LOC (15) Cl. **07-05**

(52) U.S. Cl.

USPC **D32/40**; D28/63

(58) **Field of Classification Search**

USPC D32/40–43, 46, 50–52; D28/63; D4/119
CPC .. A47K 7/02; A61H 7/002; A46B 9/02; A46B
17/06; A46B 5/021; A01K 13/002

(57) **CLAIM**

The ornamental design for a facial scrubbing device, as shown and described.

DESCRIPTION

FIG. 1 is a top perspective view of a facial scrubbing device.

FIG. 2 is a left view thereof.

FIG. 3 is a right view thereof.

FIG. 4 is a front view thereof.

FIG. 5 is a rear view thereof.

FIG. 6 is a top view thereof.

FIG. 7 is a bottom view thereof; and,

FIG. 8 is a bottom perspective view of a facial scrubbing device.
